RESILIENT CHURN SUPPORT

Arthur H. Boileau, Cedar Rapids, Iowa, assignor
to Cherry-Burrell Corporation, Chicago, Ill., a
corporation of Delaware

Original application January 3, 1939, Serial No.
249,056. Divided and this application Febru-
ary 24, 1944, Serial No. 523,753

4 Claims. (Cl. 259—S1)

1

This invention relates to churning and butterworkers. More particularly the invention relates to a resilient support for a churn and butterworker in which the churn and butterworker drum is of the rotatable type adapted preferably to rotate about its horizontal axis and in which the drum for the churn and butterworker is provided internally with fixed shelves and baffle means for the agitation, blending and working of the cream and butter.

In churning and butterworkers of the sanitary type when constructed of wood, distortion and warping of the wood may frequently occur. It is, therefore, essential that allowances be made for such possible distortion or warping of the drum or drum heads or ends of the assembled churn drum to prevent the development of undue strains in the supporting and driving means, which strains are normally brought on by such distortion or warping. It is also desirable in the construction of a sanitary wooden churn and butterworker to avoid, insofar as possible, the use of opposed metal parts, packing glands, and other similar elements on the interior of the churn and butterworker, which elements may present unsanitary surfaces and which elements if not meticulously cleaned, constitute sources of contamination of the product manufactured in such churning and butterworkers.

The accompanying drawings illustrate the aspects of the improved design in a resilient support for a churn and butterworker, which is a simple and inexpensive construction as contemplated by this invention. However, the invention is not to be limited to the specific embodiment disclosed. The features of the improved churn and butterworker illustrated in the accompanying drawings which relate particularly to the novel shelves or baffles and to the particular arrangement thereof within the drum of the churn and butterworker and the manner of supporting them upon the churn gudgeons or spiders are described and claimed more specifically in my co-pending application Serial No. 249,056, entitled, "Churn and butterworker," which application was filed January 3, 1939 now Patent No. 2,359,744, dated October 10, 1944, and of which application this is a division.

One of the principal objects of the invention is to provide a churn and butterworker having a resilient support which will accommodate expansion and contraction of the churn drum and will also accommodate the distortion or warping of the churn drum and drum heads without substantially affecting or applying stresses to the

2

churn drum supporting and driving mechanism.

Other important features of this invention will be more apparent upon the examination of the details of the construction of the improved churn and butterworker, all of which may be varied within certain limits without departing from the spirit and scope of the instant invention. The invention will be clearly described in the following description and the appended claims, reference being made to the accompanying drawings in which:

Figure 1 is a perspective view of a horizontally disposed rotatable churn and butterworker drum illustrating the general arrangement of the churn drum, the supporting framework, driving mechanism and standards.

Figure 2 is another perspective view similar to Figure 1, and in which the staves constituting the front portion of the drum of the churn and butterworker have been removed to more clearly illustrate the interior construction of the drum.

Figure 3 is a transverse sectional elevation taken along line 3—3 of Figure 2.

Figure 4 is a fragmentary sectional view taken through the shelf supporting bracket, the drum head and the end of the supporting gudgeons and end of the shelf when these various elements are in operative arrangement. Figure 4 is taken along line 4—4 of Figure 6.

Figure 5 is a fragmentary sectional view illustrating an alternative construction for supporting the shelves or baffles within the drum of the churn and butterworker and the drum head upon the gudgeon or spider whereby the shelf supporting bracket, as illustrated in part of Figure 4, is eliminated.

Figure 6 is a fragmentary sectional view taken longitudinally through the bracket end of the churn supporting gudgeon, drum head and shelf supporting bracket along the line 6—6 of Figure 4.

Figure 7 is an end elevation of a churn and butterworker provided with a resilient supporting gudgeon or spider embodying this invention.

Figure 8 is a side elevation partially in broken away section of the end of the churn and butterworker provided with a resilient supporting gudgeon as illustrated in Figure 7.

Referring to the aforementioned illustration of the invention in the improved type of churn and butterworker resilient support arrangement mounted for use preferably in a horizontally disposed rotatable drum type of churn and butterworker, the invention includes a cylindrical wooden drum of the conventional stave type generally

identified by the numeral 11. The drum or cylinder 11 is provided with opposed drum or cylinder heads or end walls 12 and 13. Suitable drum staves or confining bands or hoops 14 provided with tightenable turnbuckles 15 are placed about the outer periphery of the drum 11 at spaced intervals.

A novel improvement embodied in the invention is the manner in which the drum or cylinder 11 and the opposed drum heads 12 and 13 are supported by a resilient spider or gudgeon on the fixed churn standards. Churns and butterworkers are, of course, conventionally provided with interior shelves or baffles. Bracket blocks 17 on which the shelves or baffles are supported within the churn drum are each provided internally with a suitable bolt anchorage, such as a metal rod 18, having several threaded or tapped openings 19. The rod 18 in each instance is sealed into the longitudinally extending opening 20 of the associated block 17 by stoppers 21 as clearly illustrated in Figures 4 and 6 of the drawings. The respective bracket blocks 17 are fitted in the recesses 22 in the interior face of the cylinder heads or end walls 12 and 13. The tapped holes 19 and the bolt anchorage 18 are arranged perpendicular to the plane of the end walls 12 and 13 and are in alignment with the anchorage openings 23 through the adjoining portion of the bracket block 17 and the corresponding openings 24 in the end walls or drum heads 12 and 13. Each of the opposed drum supporting spiders or gudgeons of the type illustrated in Figures 1, 2 and 6 of the drawings includes a central hub 25 mounted in any conventional manner upon a trunnion (not shown) and having a plurality of substantially radially extending gudgeon arms 26, each of which arms is provided with an elongated terminal 27 having anchor bolt openings 28 corresponding to and in alignment with the corresponding openings 24 in the end walls 12 and 13. Each gudgeon is fixed to the associated bracket blocks 17 on the interior of the drum heads by means of anchor bolts 29, each of which bolts passes through the aligned corresponding openings 28, 24 and 23 into a tapped opening 19 to engage the associated anchor rod 18. The spider or gudgeon does not directly engage any portion of the drum 11. The drum 11 is supported upon the drum heads or cylinder ends 12 and 13 which engage the supporting spiders or gudgeons.

The trunnions (not shown) to which the drum supports or gudgeons or spiders are fixed by means of the hubs 25 may be supported in any conventional manner. Generally speaking, these trunnions are mounted in journals on standards in which the journals are preferably provided with end thrust features and in which the bearings are carried at the upper portion of the standards, such as the standards 30 and 33. As illustrated, the trunnion coaxing with the supporting spider or gudgeon fixed to the end wall 12 is carried by a suitable drive unit fixed to the standard 33 which drive unit is generally indicated by the numeral 32. Tubular bracing elements 31 join the lower portions of the vertical standards 30 and 33 to complete the rigid framework or base for the improved churn and butterworker.

The aspect of the disclosed invention which relates to the improved shelf construction and the improved manner of securing the shelves directly to the gudgeons as illustrated in the accompanying drawings is all clearly set forth in my co-

pending application Serial No. 249,056, now Patent No. 2,359,744, dated October 10, 1944, of which this is a division.

As illustrated in the drawings, the improved 5 churn and butterworker is provided with a plurality of shelves 34, 35 and 36. The ends of the shelves are supported on bracket 17 within the drum or barrel formed of the outer wall 11 and the end walls 12 and 13. The shelves are braced 10 intermediate their ends by braces 37. The shelves 34, 35 and 36 are spaced slightly from the drum wall 11 and are disposed angularly with respect to radii of the churn drum.

A splitting bar or central baffle 38 is supported 15 substantially centrally within the drum 11. The bar 38 is fixed at each end thereof to the end walls 12 and 13 in any conventional manner (not shown).

To permit determination of the progress of the 20 churning and butterworking operation, inspection windows or indicators 54 are provided at either end of the drum 11. When the butterworking operation is completed, the rotation of the churn is stopped with the churn doors 32 in the unloading 25 position as clearly illustrated in Figure 1 of the drawings. The churn may be locked in this position by swiveled pawl 43 mounted on the tubular frame element 31 by clamp 44. The locking is accomplished by engaging the pawl 43 with the rack 45 mounted on the adjacent end of the drum 11 by bolts 46. To facilitate emptying the drum 11 there is provided a conventional type of discharge outlet 55 mounted in one of the 30 end walls or drum heads 12 or 13 adjacent the outer periphery thereof.

The shelf supporting arrangement illustrated 35 in Figures 4 and 6 involves the use of the bracket 17 at each end of a shelf. The bracket 17 is partially fitted into a corresponding recess 22 in the end wall 12 or 13 and there held rigidly in place by the gudgeon anchor bolts 29 which are fixed to the anchor bar 18. The shelves resting upon the brackets 17 are fixed thereto by countersunk 40 bolts 47 extending through the shelves into the brackets 17 and suitably threaded into the bolt anchorage 18. Stoppers 48 are fitted in the countersunk 45 openings of the shelves to seal therein what would otherwise be an exposed metal surface of the bolts 47.

An alternate construction for the supporting 50 of the shelves in the churn barrel is shown in Figure 7 of the drawings. In the alternate construction shown in Figure 7, an edge of the bracket 17 is replaced by an end of one of the shelves 34, 35 or 36. By fitting such replacing 55 end of a shelf, as for example, shelf 34', tightly into the recess 16, the likelihood of splitting the end of the shelf by tightening the associated bolt 29, which tightening applies pressure to the bolt anchorage 18' provided in the inner openings in 60 such end of the shelf is substantially avoided. In this alternative construction, it is, of course, not necessary to separately fix each end of the shelf to its associated bolt anchorage 18'.

In Figures 1 to 6 of the drawings, the gudgeon 65 illustrated may be of the cast or rigid type. In Figures 7 and 8 there is disclosed specifically the improved resilient type of gudgeon or supporting spider. The improved gudgeon or supporting 70 spider includes the trunnion or hub 25' to which wide but relatively thin radial, preferably sheet metal, arms 49 are affixed in a suitable manner, such, for example, as by rivets 50. The terminals 51 at the ends of each of the radial arms 49 are 75 substantially the same width as the terminals

27 hereinbefore referred to and as illustrated in association with the cast type of gudgeon. The terminals 51 are provided with anchor bolt openings 52 similarly spaced and arranged as are the anchor bolt openings 28 associated with the cast gudgeon terminal 27. The anchor bolts 29 extend into the bracket 17 through the anchor bolt openings 52 in the improved resilient type of churn and butterworking gudgeon. The anchor bolts 29 secure the improved resilient type of gudgeon to the drum head 12 or 13 by engagement of the bolts 29 with the bolt anchorage 18 in the bracket 17. To properly position or space the modified supporting resilient type of spider or gudgeon with relation to the end wall 12 or 13 of the churn drum, spacing bars 53 having the necessary openings for the anchor bolts 29 corresponding to the openings 52 in the terminals 51 are provided. The spacing bars 53 are positioned intermediate the end walls 12 and 13 of the churn and the adjacent spider arm terminals 51.

The improved resilient churn supporting gudgeon or spider which is rigidly secured to the shelf supporting bracket 17 or to the adjacent ends of the shelves 34, 35 and 36 provides distinct structural advantages in the construction of a wooden type churn and butterworker in which the wooden elements are most commonly susceptible to warpage. The resilient churn and butterworker supporting gudgeon is capable of absorbing such common structural defects as slight misalignment of journals as well as the misalignment sometimes resulting from the warping of the churn drum walls or drum heads. The improved gudgeons tend to relieve the driving mechanism, driving coupling and supporting bearings of undue wear and undue strain which commonly results from such misalignment, whether the misalignment is brought about by slight structural defects or from churn drum or drum head warpage. The resilient type of churn supporting gudgeon also allows for the normal expansions or distortions which take place during the normal operation of the churn and butterworker.

It will, of course, be understood that various detailed alterations and arrangements of the principal elements which have been described and as illustrated in the accompanying drawings may be made by those skilled in the art within the scope of the invention as set forth in the appended claims.

The invention is hereby claimed as follows:

1. A churn and butterworker comprising a wooden drum and drum ends, rotatable supporting spiders supported on bearings and fixed to the drum ends of said drum and having resilient radially extending members adapted for flexing axially of said drum, said members being so constructed and arranged as to avoid undue strain on said supporting bearings by the swelling or distortion of the elements of the wooden churn drum incidental to the normal operation of the churn and butterworker.
2. A churn comprising a wooden drum, and rotatable supporting spiders fixed to the ends of said drum and having resilient radially extending members adapted for flexing axially of said drum, said members being so constructed and arranged as to avoid undue strain on the supporting bearings by the swelling or distortion of the elements of the wooden churn drum incidental to the normal operation of the churn.
3. In a churn, the combination of a drum including end walls, a supporting framework, trunnions mounted in said framework, hubs supported on said trunnions, and resilient outwardly extending supporting arms capable of flexing axially of said drum and positioned intermediate said hubs and said end walls for rotatably supporting the same upon said trunnions.
4. A device of the class described comprising, in combination, a drum, a supporting framework, rotatable hub means supported upon said framework, and resilient arms extending from said hub means to said drum for rotatably supporting said drum upon said hub means, said resilient arms being capable of flexing axially of the axis of rotation of said hub means.

ARTHUR H. BOILEAU.
